UNITED STATES PATENT OFFICE.

EMLEN AUGUSTUS FRANKLIN AND GUSTAVE JOHANN DALEY, OF FORT COLLINS,
COLORADO.

JIGGING BEET WASHER AND ROCK CATCHER.

Application filed June 9, 1919. Serial No. 302,963.

To all whom it may concern:

Be it known that we, EMLEN AUGUSTUS FRANKLIN and GUSTAVE JOHANN DALEY, citizens of the United States, residing at Fort 5 Collins, in the county of Larimer and State of Colorado, have invented a new and useful Jigging Beet Washer and Rock Catcher, of which the following is a specification.

This invention relates to apparatus for preparing beets for the manufacture of sugar, and an object is to remove from the beets all rocks which may accompany the beets as they are delivered to the factory, thus to absolutely prevent any rocks or other heavy 15 solids from being carried into the beet cutters.

Sugar beets are of such specific gravity that a quantity of beets moving along a flume filled with water will be practically submerged, and a current of water sufficient to carry the beets along the flume is apt to also carry rocks along the flume if said rocks are dumped into the flume with the beets, and an object of this invention is to move the beets 20 along the flume, and to retain the rocks so that they may be cleaned out of the flume after the beets have been discharged.

This invention is broadly new, basic and primary in that means are provided in connection with the flume whereby the water in the flume will be subjected to wave action tending to successively raise and lower the beets as they pass down along the flume, thereby floating the beets along by a movement which allows the rock to remain in the bottom of the flume, which is provided with a grating to support the rocks underneath the beets, thus floated along. Said wave-like motion of the water in the flume is 30 caused by means at the side of the flume, and communicating with the flume through said grating, the flume being separated into compartments by transverse riffles spaced along the flume, and over which riffles the beets 35 must rise as they move down along the flume.

An object of the invention is to provide means for simultaneously cleaning the beets from attached earth and from rock accompanying the discharge.

Another object is to make satisfactory provision for discharging the dirt removed from the beets.

Further objects, advantages and features

of the invention may appear from the accompanying drawings, the subjoined detailed description and the appended claims.

The accompanying drawings illustrate the invention.

Figure 1 is a plan of the apparatus.

Fig. 2 is a fragmental side elevation.

Fig. 3 is a transverse section on line α^3 Figs. 1 and 2, showing the piston 12 at the end of its upward stroke in which movement it sucks water out of the flume.

Fig. 4 is a view of the bottom portion of Fig. 3 parts omitted and parts broken away; also showing the piston 12 at the end of its downward stroke in which the water will be forced back into flume as indicated by the 70 arrows.

The flume 1 may be three feet more or less in depth, and eighteen inches more or less in width and about fifteen feet long; but other dimensions may produce the same results, consequently we do not desire to be limited to any specific size.

The flume is provided with smooth side walls 2, 3 extending a desired length from the inlet 4 to the outlet 5. The inlet end 4 and outlet end 5 are connected to similar walled flumes not shown so that a stream of water is continually passing through the flume 1; and the beets to be washed are dumped into the flume at the inlet end. 80 The gratings 6 are preferably formed of metal strips spaced apart and secured to the angle irons 6' in the bottom of the flume; however these gratings may be of any requisite construction and arranged at the bottom of the flume.

Between the gratings 6 there are transverse riffles 7 of about six inches more or less in width; and they are arranged to separate the flume into the rock catching compartments 8, 95 and each of said compartments is provided with a sump 9 that having connection through a lateral 10 with a piston chamber 11, in which piston 12 is arranged to reciprocate, and for this purpose said piston is 100 shown as being pivotally connected through a connecting rod 13 with an eccentric band 14 operated by an eccentric 15 mounted on a shaft 16, which is driven by power through any suitable means, as the sprocket wheel 105 17, and connections, not shown, to a motor, not shown.

Said shaft 16 is provided with a plu-

rality of eccentrics 15, 15' 15" 15"" staggered on the shaft 16 for successive operation of the pistons 12, 12' 12" and 12" as the shaft rotates, which pistons are shown 5 as square in cross section, and which fit the chambers 11 and which successively move the water to and from the flume 1 through the grates 6 and into and out of the laterals 10 and sumps 9. The water's wave-like upward 10 and downward motion produced by the operation of the pistons, raises and lowers the beets successively in the successive compartments and the beets are thus moved along over the riffles 7 while the heavy materials, 15 such as rocks, pieces of iron, if any of the like are retained within the compartments.

Each sump 9 is provided with an outlet 18 closed by a valve 19 which is operated through a suitably adjusted lever arrangement 20, provided with a handle 21 within the reach of the operator.

A by-pass 22 is provided alongside the flume on the side opposite to the piston chambers 11, and gates 23, 24 are provided 25 to shunt the water from the inlet flume 25 around the washing flume 1 and to discharge the water thus shunted into the outlet flume 26.

In practical operation the gates 23, 24 will 30 be closed so that the water will flow directly from the inlet flume 25 through the washing flume 1 and out at the outlet flume 26, and beets will be dumped into the flume at the inlet end of the flume. The shaft 16 is 35 rotated thus causing the water in the washing flume to rise and fall in the successive compartments, whereby the beets are carried along over the riffles 7 and the rocks and other heavy matter are retained in the 40 compartments.

After the earth becomes separated from the beets it falls through the gratings 6 into the sumps 9 and from time to time the operator will operate the handles 21, thus 45 opening the valves 18 and discharging the soil from the sumps. The handles 21 may be operated from time to time as required. When the accumulation of rock in the wave 50 compartments becomes sufficient to require removal, the shunting gates 23, 24 will be swung across the flume to shunt the water through the shunting flume, then the rocks 55 may be cleared out of the wave compartments; shunting gates return to allow the water to flow through the flume, and further charges of beets will then be cleansed.

We claim:

1. A jiggling rock catcher comprising a flume, having a grate at the bottom, riffles 60 separating the lower part of the flume into compartments, means for supplying water to the flume, means for causing an upward and downward action of the water as it flows

through said flume, and means for shunting the water around said flume for the 65 purpose specified.

2. In a jiggling device, supply and discharge flumes, a washing flume and a by-pass flume each having adjacent communicating connections both with said supply 70 and discharge flumes, and gates adapted to close the communications between the supply and discharge flumes either with said washing flume or with said by-pass flume, said gates when closing the washing flume forming a 75 slanting wall to turn the water into the by-pass flume and from said flume into the discharge flume.

3. In a beet washer, the combination of a flume, having a grate at the bottom, a sump 80 beneath the grate, a piston chamber communicating with the sump, a piston reciprocating in the chamber to cause an upward and downward action of liquid in said flume, a by-pass, and means for shunting liquid 85 from said flume into said by-pass.

4. The combination with a flume adapted to carry a stream of water and having a grate at its bottom, of a sump, communicating with the flume through the grate, a shaft 90 extending alongside the flume, eccentrics on said shaft, piston chambers arranged below said shaft and communicating with the sumps, alternating pistons connected with the eccentrics respectively and operating in 95 said chambers, a by-pass and means for shunting water from said flume into said by-pass.

5. The combination with a flume adapted to carry a stream of water and having a 100 grate at its bottom, of a sump communicating with the flume through the grate, a shaft extending alongside the flume, eccentrics mounted on the shaft in staggered relation for operating pistons in alternate order, and 105 means for shunting water around said flume and grate.

6. A jiggling rock catcher comprising a flume, grates in the bottom of the flume, 110 riffles between said grates, a sump under each grate, alternating pistons at the side of the flume whereby water in the flume will be sucked through part of said grates into corresponding sumps and discharged from the other sumps through their corresponding grates into the flume, and a by-pass at the side of said flume opposite said pistons.

In testimony whereby, we have hereunto set our hands at Fort Collins, Colorado, this 120 22 day of May, 1919.

EMLEN AUGUSTUS FRANKLIN.

GUSTAVE JOHANN DALEY.
